COSTUMER

Robert W. Schier, Northfield, and Leonard D. Singer,
Chicago, Ill., assignors to Krueger Metal Products, Inc.,
Green Bay, Wis., a corporation of Wisconsin

Filed Mar. 18, 1968, Ser. No. 11,023

Term of patent 14 years

Int. Cl. D6—01

U.S. Cl. D33—8

FIG. 1 is a view in side elevation of a costumer embodying our improved design.

FIG. 2 is a view thereof in cross section on the line 2—2 of FIG. 1.

FIG. 3 is a view thereof in cross section on the line 3—3 of FIG. 1.

FIG. 4 is a fragmentary view thereof in perspective showing the costumer in section on the line 4—4 of FIG. 1.

FIG. 5 is a fragmentary detail view in section on the line 5—5 of FIG. 3.

We claim:

The ornamental design for a costumer, as shown.
